BUTTER SPREADER FOR CORN

George Becker, New York, N. Y., assignor to Alan Sales Corporation, Woodhaven, N. Y., a corporation

Application May 23, 1955, Serial No. 36,158

Term of patent 3½ years

(Cl. D44—29)

FIG. 1

FIG. 3

Fig. 1 is a perspective view of a butter spreader for corn, showing my new design and showing the cover in open position;

Fig. 2 is a perspective view thereof showing the cover in closed position; and

Fig. 3 is a perspective view showing the bottom portion thereof.

I claim:

The ornamental design for a butter spreader for corn, substantially as shown and described.
